(57) **CLAIM**

The ornamental design for loader bucket forks, as shown and described.

DESCRIPTION

FIG. 1 is a perspective view of loader bucket forks showing my new design;

FIG. 2 is a front view thereof;

FIG. 3 is a side view thereof;

FIG. 4 is a top view thereof; and,

FIG. 5 is a bottom view thereof.

The broken lines shown in the drawings represent portions of the loader bucket that form no part of the claimed design.
